WARP-UNITING MACHINE

Martin N. Noling, Rockford, Ill., assignor to
 Barber-Colman Company, Rockford, Ill., a corporation of Illinois

Application May 4, 1935, Serial No. 19,799

17 Claims. (Cl. 28—49)

This invention relates to machines for uniting warps, and refers particularly to machines of the portable type disclosed in the Colman Patents Nos. 1,069,082, 1,082,474 and 1,149,499.

5 The general object of the invention is to make improvements in those features which relate to the handling of the warp threads preparatory to and after the actual uniting of the threads. Among the particular objects of the invention 10 are to provide means on the main frame of the machine for so supporting the old-warp carriage that it may be conveniently supported in and out of operative position and moved from one such position to the other; means to prevent 15 the old-warp carriage from being accidentally or inadvertently moved into or out of its inoperative position while the mechanism carriage is out of its idle or initial position; and means for adjusting the two sheets to bring the threads 20 thereof into parallelism.

In the accompanying drawings:

Figure 1 is a front elevation of a portable warp-tying machine embodying the features of my invention, the warp-tying mechanism, proper, being omitted.

Fig. 2 is a plan view.

Fig. 3 is a section on line 3—3 of Fig. 2.

Fig. 3^a is a fragmental plan section on the line 3^a of Fig. 3.

30 Fig. 4 is a fragmental view of one end of the machine.

Fig. 5 is a fragmental end elevation of the machine.

Fig. 6 is a fragmental perspective view of two 35 of the warp clamps and the associated ribbon bars.

Fig. 7 is a fragmental front elevation, somewhat diagrammatic, of the machine, showing the warp carriage in its out-of-the-way position, and 40 illustrating the united threads as supported under tension for inspection of the knots.

The present improvements are herein disclosed as embodied in a portable machine especially adapted to be placed behind a loom requiring warp replenishment. That side of the machine which is toward the loom will be referred to as the loom side, and the opposite side as the front side. The end of the machine from which the uniting of the warps is started will be 45 termed the head end, and the opposite end will be called the foot of the machine.

The supporting framework of the machine comprises a base 1 mounted on wheels 2 and 3, two uprights 4 and a bed 5. As shown in Fig. 5, 50 the uprights 4 are cut away at the loom side in

order to allow the machine to be set as close as possible to the loom. This is an advantage where the loom is close to a supporting post of the building. 7 is a brake to hold the machine steady while the warps are being manipulated and tied. A handle 8 for use in moving the machine about in the mill is detachably connected to the head end of the bed, so that it may be removed after the machine has been stationed behind the loom, thus giving the operator 10 free access to the head end of the machine.

The warp-uniting mechanism (not shown) is mounted on a mechanism carriage that is arranged to travel on a gib 9 extending longitudinally of the bed 5. The over-all dimension or outline of the warp-uniting mechanism and its carriage is indicated by the dotted line 10 in Fig. 5. For a full disclosure of a form of mechanism which may be used, reference may be made to the Colman Patent No. 1,082,474.

Portions of the two warps to be united are supported in the path of the warp-uniting mechanism. The supports for the new warp comprise a pair of clamps 11 and 12 (Figs. 5 and 6) and a "ribbon bar" 13 carried above the bed 5 on posts 14. The old warp threads are supported by a pair of clamps 15 and 16 and a ribbon bar 17 which form parts of a warp carriage designated as a whole by the number 18. The framework of the warp carriage includes two yokes or inverted U-shaped members 19. For a description of the clamps and the ribbon bars reference may be made to the Colman Patent No. 1,082,474.

In order that the threads held in one pair of clamps may be brought into parallelism with those held in the other pair of clamps, the clamps 11 and 15 are mounted on the ribbon bars 13 and 17 for longitudinal adjustment. As shown in Fig. 6, the clamp 15 extends through a guide 19^a and has a gib 19^b that slides in a groove in the ribbon bar 17. To one end of the clamp 15 is fixed a screw 19^c. An adjusting nut 19^d on the screw 19^c has a peripherally grooved collar 19^e that engages an abutment 19^f on the ribbon bar 17. Turning the nut 19^d causes the clamp 15 to move longitudinally of the ribbon bar. The clamp 11 is similarly mounted and adjusted.

When the warp carriage is in operating position, it is supported on rollers so that it may be moved sufficiently to compensate for variations in the spacing of the old-warp threads and for the difference in width or "spread" of the two warps. In the drawings the rollers at the loom side are numbered 20 and 21 (Fig. 2); they are mounted in brackets attached to opposite ends 55

of the ribbon bar 17 (Fig. 6). The rollers at the front side are numbered 22 and 23 and are mounted in brackets fixed to opposite ends of the clamp 16 (Fig. 7). The rollers 20 and 21 run on grooved trackways 24 and 25, respectively. The roller 23 runs on a flat trackway 26. The trackways 24, 25 and 26 may be supported from the bed 5 in any preferred way; herein the trackways 24 and 25 are fixed to the ribbon bar 10 13 (Figs. 5 and 6) and the trackway 26 is fixed to the clamp 12 (Fig. 7).

Means is provided for supporting the warp carriage so that it may be lifted out of its operating position in order to facilitate the preparation and mounting of the warps, or in other words, the loading of the machine. Said means comprises an arm 27 which is bifurcated at one end to span the head end of the bed 5. The bifurcated end of the arm 27 is fixed upon a pivot shaft 28 (Fig. 3) which is journaled in the bed 5. Extending from the arm 27 are two parallel rods 29 (Fig. 2) which pass loosely through the yokes 19. The outer ends of the rods 29 are united by a casting 30 that constitutes a handle for use in raising and lowering the warp carriage. On the arm 27 is a trackway 31 for the roller 22 (Fig. 7).

To counterbalance the weight of the warp carriage, a torsion spring 32 (Fig. 3) is placed upon the pivot shaft 28, one end of the spring bearing against the bed 5, and the other end being attached to an adjusting collar 33, the latter being fixed to the shaft by one or more set screws 34. The arm 27 is held down in operative position by means of a manually-operable latch 35 pivoted on the bed 5 at 36 and engaging a block 37 on the arm 27. The block 37 is held by the latch 35 against a bumper or stop plate 38 on the bed 5, the parts 37 and 38 serving to locate the arm 27, trackway 31 and rods 29 accurately so that the warp carriage shall rest upon the trackways 24, 25, 26 and 31 without being pressed against the trackways 24, 25 and 26 by the rods 29. There is clearance between the rods 29 and the yokes 19 when the warp carriage stands on its trackways. Rubber bumpers 39 on the bed 5 locate the arm 27 in its thrown-out position.

To prevent lifting of the warp carriage after the mechanism carriage has been advanced to its work and until the mechanism carriage has been returned to its idle position, an interlock is provided between the mechanism carriage and the arm 27. This interlock comprises a plate 40 (Figs. 3 and 3^a) fastened to the arm 27 and a latch bolt 41 mounted on the bed 5, said bolt being urged by a spring 42 into engagement with the plate 40 when the arm 27 is swung against the bumper 38. When the mechanism carriage is pushed back to its initial position at the head end of the machine after completing the union of two warps, a cam or projection 43 on said carriage engages a pin 44 on the latch bolt 41 and pulls the bolt away from the plate 40, thus leaving the arm 27 and the warp carriage free to swing upwardly when the latch 35 is manually withdrawn by the operator. A spring buffer 45 (Fig. 2) on the arm 27 serves to cushion the descent of the warp carriage when it slides down the rods 29 as the arm 27 rises. A similar buffer 46 is provided on the bed 5 to cushion the shock when the mechanism carriage is returned to its initial position.

Means is also provided to prevent the warp carriage 18 from being lowered in case the mechanism carriage has been moved out of its initial

position. Said means comprises the plate 40 and the latch bolt 41. As shown in Fig. 7, the bolt 41 is adapted to lie in front of (i. e., below) the plate 40 so as to prevent the arm 27 from being swung down. The bolt 41 is beveled at 41 5 (Fig. 3^a) to coact with the lower edge of the plate 40. As before explained, when the mechanism carriage is in its initial position, the cam 43 holds the bolt 41 in ineffective position, so that the warp carriage may be raised or lowered. 10

The operation of the apparatus herein disclosed may be summarized as follows: The machine is stationed behind the loom in position to operate upon the first group of warp threads to be tied, and held by the brake 7 against displacement. The handle 8 is removed, and the arm 27 is swung up to place the warp carriage in its out-of-the-way position. 15

After the warp threads have been secured in the clamps 11, 12, 15 and 16 and tensioned, the threads of the two sheets are brought into parallelism by longitudinal adjustment of one or both clamps 11 and 15, after which the threads are deflected by operating the ribbons as described in the Colman Patent No. 1,082,474. 20

The mechanism carriage is then advanced into position for operation upon the threads. Such positioning of the mechanism carriage allows the automatic latch 41 to latch the warp carriage against upward displacement. After the portions of the warps held in the clamps have been united, the mechanism carriage is returned to its idle position, the united threads are released from the clamps 11 and 15, the latch 35 is disengaged and the warp carriage swung up to the 35 position shown in Fig. 7.

It will be seen that the warp carriage 18 can be raised or lowered only when the mechanism carriage is in its out-of-the-way or initial position, thus protecting the mechanism on the 40 mechanism carriage from damage by the warp carriage.

While the present invention has been described in connection with a portable machine, it will be understood that certain features of the 45 invention may be applicable to stationary machines. It will also be understood that various changes may be made in the construction herein disclosed without departing from the scope of the invention as defined in the appended claims. 50

I claim as my invention:

1. A warp-uniting machine comprising a bed, a mechanism carriage mounted to travel on the bed, a support pivotally mounted with relation to the bed at one end of the latter, a warp carriage slidably connected to the support, said support, when in one position, holding the warp carriage in operative relation to the bed, and, when in another position, holding the warp carriage in an elevated withdrawn position, a spring-actuated 60 latch bolt coacting with said support to latch it in either of said positions, and a cam on the mechanism carriage to withdraw the bolt.

2. A warp-uniting machine comprising a bed, a mechanism carriage mounted to travel on the 65 bed, a support pivotally mounted with relation to the bed at one end of the latter, a warp carriage slidably connected to the support, said support, when in one position, holding the warp carriage in operative relation to the bed, and, when in another position, holding the warp carriage in a withdrawn position, a spring-actuated latch bolt coacting with said support to latch it in one of 70 said positions, and a cam on the mechanism carriage to withdraw the bolt.

3. A warp-uniting machine comprising a bed, a mechanism carriage mounted to travel on the bed, a support movably mounted with relation to the bed, a warp carriage slidably connected to the support, said support, when in one position, holding the warp carriage in operative relation to the bed, and, when in another position, holding the warp carriage in a withdrawn position, means to latch it in one of said positions, and a cam on the mechanism carriage to operate said means. 5
4. A machine for operating upon warp threads comprising a bed, a mechanism carriage mounted to travel on the bed, a warp support movable into and out of operative relation to the bed, means 10 to hold the warp support in either of said positions, and a cam on the mechanism carriage to render the holding means ineffective. 15
5. A machine for operating upon warp threads comprising a support for warp threads, said support being movable into and out of operative position, a traveling mechanism to operate upon the threads, and means controlled by said mechanism for preventing movement of said support out of one of said positions, except when said mechanism is at a certain point in its travel. 20
6. A machine for operating upon warp threads comprising a support for warp threads, said support being movable into either of two positions, a mechanism to operate upon the threads, and means controlled by said mechanism for holding said support in either of its positions. 25
7. A machine for operating upon warp threads comprising a support for warp threads, said support being movable into either of two positions, a mechanism to operate upon the threads, said mechanism being movable transversely of the threads from an idle position, and means for holding said support in either of said positions, said means being rendered ineffective by said mechanism when the latter is in its idle position. 30
8. A machine for operating upon warp threads, comprising two parallel clamps to hold a sheet of threads extending from one clamp to the other, and means for longitudinally adjusting one clamp 35 with relation to the other to vary the angular relation of the threads to the clamps. 40
9. In a warp-uniting machine, a bed, a mechanism carriage mounted to travel along the bed, a support pivotally mounted with relation to the bed at one end of the latter, and a warp carriage slidably mounted on the support, said support, when in one position, holding the warp carriage in operative relation to the path of movement of the mechanism carriage, and, when in another position, holding the warp carriage in an elevated withdrawn position. 45
10. A machine for operating upon warp threads comprising a support for warp threads, said support being movable into an operative and a withdrawn position, a mechanism to operate upon the threads, and means controlled by said mechanism for locking the support in its withdrawn position. 50
11. A machine for operating upon warp threads comprising a support for warp threads, said support being movable into and out of operative position, a traveling mechanism to operate upon the threads, and means controlled by said mechanism for preventing movement of said support out of its operative position except when said mechanism is at the starting end of its travel. 55
12. In a warp-uniting machine, a bed for supporting a traveling mechanism for movement longitudinally thereof, a pair of new-warp clamps mounted on the bed, a warp carriage mounted for movement above the bed, a pair of old-warp clamps mounted on said carriage and movable as a unit relative to the new-warp clamps to compensate for unequal spacing of the threads of the two warps, and means for adjusting one of the 10 clamps of one of said pairs relative to the other clamp of said pair so as to vary the angular relation of the threads of the two warps. 15
13. A warp-tying machine having means for holding a series of new-warp threads and a series of old-warp threads, said means including two clamps one for each of said warps, two ribbon bars slidably supporting said clamps, and an operative connection between each of said clamps and its ribbon bar for producing relative longitudinal movements between the clamps while the warps are being united. 20
14. A warp-tying machine having means for holding a series of new-warp threads and a series of old-warp threads, said means including a pair 30 of parallel supports one for each of said warps, a warp clamp mounted for movement longitudinally of each of said supports, and a screw-threaded connection between each of said clamps and its support for producing relative longitudinal movements between the clamps of the two warps. 35
15. In a warp-tying machine, an elongated support, a warp clamp mounted on said support for movement longitudinally thereof, said support being extended beyond one end of the clamp, and means including a manually rotatable element operatively connecting the extended end of said support with the adjacent end of said clamp to produce relative movement between the clamp 40 and the support. 45
16. In a warp-tying machine, a frame, a support rigid with the frame, a warp clamp mounted on said support for longitudinal movement, and a screw-threaded connection between said support and clamp including a manually operable element at one end of the clamp operative to impart longitudinal movements to the clamp relative to the support. 50
17. In a warp-tying machine, an elongated support, a warp clamp mounted on said support for longitudinal movement, said support being extended beyond one end of the clamp, and a screw-threaded connection including a nut held against axial movement relative to said extended 55 end of the support, and a screw fixed on the adjacent end of the clamp and engaging with said nut. 60

MARTIN N. NOLING.
